UNITED STATES PATENT OFFICE.

CHARLES GATES, OF LOUISVILLE, KENTUCKY, ASSIGNOR OF ONE-HALF TO HENRY G. TROMPETER, OF LOUISVILLE, KENTUCKY.

SAFETY HAT-PIN.

1,111,741.

Specification of Letters Patent. Patented Sept. 29, 1914.

Application filed March 19, 1913. Serial No. 755,329.

To all whom it may concern:

Be it known that I, CHARLES GATES, a citizen of the United States, residing at the city of Louisville, in the county of Jefferson and 5 State of Kentucky, have invented a certain new and useful Improvement in Safety Hat-Pins, of which the following is a specification.

This invention relates to hat-pins adapted 10 to be used by ladies for fastening their hats on their heads.

An object of this invention is to construct 15 a hat-pin whereby when the same has been placed in a hat it will be impossible for the pin to become detached from the hat.

A further object is to provide a removably attached device for a pin which is adapted to be placed upon the point of the pin and be securely held in position thereon 20 by means within the device.

Another object is to provide a device adapted to receive and hold the points of pins, or other pointed instruments, whereby 25 the same are retained in position, protected from injury and prevented doing injury, and the many advantages of my device will be apparent from the following description taken in connection with the claim.

Reference will now be had to the drawing 30 accompanying, wherein like numerals of reference designate corresponding parts in the several views, in which—

Figure 1, is a side elevation with the ball in position. Fig. 2 a similar view showing 35 the removable ball in longitudinal section. Fig. 3 a perspective of the blank from which the tube is formed. Fig. 4 a perspective of a modified form from which the tube may be formed. Fig. 5 a perspective of the tube 40 as formed from the blank shown in Fig. 3. Fig. 6 a perspective of the tube as formed from the blank shown in Fig. 4.

Referring to the drawing the reference 45 numeral —1— designates a pin having a fixed head —2— and removable head —3—. These heads are illustrated as being plain spheres, or balls, but it is obvious that they may be ornamented in any manner desirable or may be of any suitable shape.

50 The removable head, or ball, 3, has arranged within it a tubular shaft —4— having a flaring, or funnel shaped mouth —5—, that may be formed integral with the tube as shown in Fig. 5, or it may be a sepa-

rate truncated cone shaped piece held in position on the end of the tube by means of extensions —6— from the body of the tube. The tube is secured to the interior surface of the shell by suitable means, such as a glob 55 of solder —9—. The tube is preferably 60 formed by rolling a blank as —7— of flexible material loosely into a tube the internal diameter of which is the same as that of the pin 1. The blank 7 being coated, on what will be the inner side of the tube when 65 formed, with a layer of tough, elastic friction material —8—. I have found damar varnish to be a suitable material to use to produce the requisite friction, but I do not 70 wish to be understood as limiting myself to that material as my invention contemplates the use of any material that spread on the interior of the tube 4 will furnish the necessary friction to oppose the entrance of the 75 pin thereinto and conversely resist its withdrawal.

I have illustrated my invention as applied to a hat-pin, and in this instance after the hat-pin has been passed through the hat the removable ball is placed on the pointed end 80 of the pin whereby the pin will be prevented from being lost, or removed from the hat unbeknown to the person wearing the same. And the point of the pin will be prevented from injuring objects that it might come in 85 contact with. The removable ball may be employed in connection with other types of pins than that illustrated and it is obvious that the construction of the same is susceptible 90 of various changes which will be permissible by the appended claim.

Having described my invention so that any one may make and use the same, I claim;—

An article of manufacture, comprising a 95 hollow shell having an opening, a loosely coiled tube secured by one end to the inner periphery of the shell and in alinement with said opening, a flaring entrance secured to the outer end of the tube and lying within 100 the shell, the interior of the tube being coated with damar varnish to increase the resistance offered to the withdrawal of a pin.

CHARLES GATES.
